UNITED STATES PATENT OFFICE.

RALPH K. MAKER, OF PROVIDENCE, RHODE ISLAND, ASSIGNOR TO B. A. BALLOU AND COMPANY, INC., OF PROVIDENCE, RHODE ISLAND, A CORPORATION OF RHODE ISLAND.

PIN.

1,031,355.

Specification of Letters Patent.

Patented July 2, 1912.

Application filed April 1, 1912. Serial No. 687,680.

To all whom it may concern:

Be it known that I, RALPH K. MAKER, a citizen of the United States, and resident of the city of Providence, in the county of 5 Providence and State of Rhode Island, have invented certain new and useful Improvements in Pins, of which the following is a specification.

This invention relates to that class of pins 10 commonly known as cuff or beauty pins, the same being more especially adapted to be made of the more precious metals, such as gold or silver, and of the so-called one-piece construction, in which both the joint and 15 catch members are formed integral with the body of the pin.

The object of the invention is to provide a pin stem having an elongated thin flat-sided head pivotally mounted between the joint 20 ears of the pin, the lower edge of the head being recessed or notched to receive a stop pin which passes laterally through the shell and through said recess to be engaged by its walls, thereby providing both a front and 25 a back stop for the stem by the use of but a single pin.

With these and other objects in view, the invention consists of certain novel features of construction, as will be more fully described and particularly pointed out in the 30 appended claim.

Of the accompanying drawings: Figure 1— is an enlarged side elevation of a pin with the body partly broken away to better 35 illustrate my invention. Fig. 2— is an enlarged detail, partly in perspective, of a pin-stem made after my improved construction. Fig. 3— is a section on line 3—3 of Fig. 1.

Referring to the drawings, 10 designates 40 the body of the pin which is more particularly adapted to be struck up complete from sheet metal, preferably of the more precious metals such as gold and silver, the same being designed to be made of the so-called 45 one-piece construction in which the catch member 11 and joint ears 12—12 are all formed integral with the body portion.

An essential feature of my invention is the provision of a pin-stem 13 having a thin 50 elongated head 14 with flattened sides, said head being pierced at 15 to receive the pivot pin 16 and also notched or recessed as at

17 on its lower edge, said notch being preferably of an inverted V-shape forming practically two downwardly extending legs 55 21—22.

Another feature of the invention is the provision of a stop pin 18 which is adapted to pass through the walls of the shell near where the joint ears extend outward from 60 the body portion, said pin also extending through the notched portion 17 between the legs 21—22 of the pin stem whereby when the stem is raised the required distance the rear wall 19 of the notch or leg 22 will engage this stop pin to limit the upward motion of the stem, and when brought downward the wall 20 of this notch or leg 21 will engage the stop pin on the opposite side and form a fulcrum to limit the downward motion of the pin-stem to provide the necessary 70 tension when the point of the stem enters the catch member in the opposite end of the pin body. This stop pin, after being inserted, is preferably headed over or riveted by 75 being pinched by a pair of pliers.

In making solid gold pins of this character it is necessary that all portions of the pin should be of the same material, and it is also very desirable that the pin may be 80 constructed of very light and thin material and at the same time possess the required strength in all its parts. It is therefore found advantageous to provide a pin-stem with a thin flattened head with all of the 85 surplus stock removed, the downwardly projecting portion being recessed to receive the stop pin 18, which single pin co-operating with the legs 21 and 22 of the pin-stem performs the double function of forming both 90 a front stop and a back stop for the pin-stem.

The device is extremely simple and inexpensive in construction and effective in its 95 operation.

By the word "shell" in the specification and claim it is understood that I include both the body portion and also the joint ears which are integrally connected thereto.

I claim:

In a pin of the character described, a shell or body portion having a pair of integral joint ears, a pin-stem having a thin flat head with a downwardly projecting por-

tion and pivotally mounted between said ears, the lower edge of said head being recessed or notched, and a stop pin passing laterally through the shell and through the recess in said head to be engaged by the recess walls and provide both a front and a back stop for the pin-stem.

In testimony whereof I affix my signature in presence of two witnesses.

RALPH K. MAKER.
